UNITED STATES PATENT OFFICE.

JAMES A. CAMERON, OF BROOKLYN, NEW YORK, ASSIGNOR TO CAMERON MACHINE COMPANY, OF BROOKLYN, NEW YORK, A CORPORATION OF NEW YORK.

SLITTING MEANS.

Application filed September 21, 1927. Serial No. 220 870.

This invention relates to slitting means and particularly of the type known as overlapping shear-cut slitting means, and has for its main object and feature maintaining the shears in overlapping relation notwithstanding "whipping" of the shaft or shafts carrying the slitting elements.

In the accompanying drawings the invention is disclosed in several concrete and preferred forms in which

Fig. 1 is a view, partly in elevation and partly in section, of a slitting device embodying one form of the invention.

Figs. 2, 3 and 4 are views similar to Fig. 1 embodying modified forms of the invention.

Fig. 5 is a transverse sectional view particularly of Fig. 4 but may be considered as illustrating a transverse section of any of the constructions shown in Figs. 1 to 4 inclusive.

Fig. 6 is a detail sectional view of a flexible coupling means that may be employed in connection with the invention.

Fig. 7 is a view similar to Figs. 1 to 4 inclusive but showing a still further modified form of the invention.

Fig. 8 is a detail sectional view substantially on the plane of line 8—8 of Fig. 7.

Fig. 9 is a detail sectional view substantially in the plane of line 9—9 of Fig. 7.

1 and 2 indicate two shear-cut members in overlapping relation said members consisting of a set of overlapping shears of a well-known type, and in machines of this type it is customary to provide a plurality of such sets of shears to slit a web of flexible material lengthwise. One of the members, as 1, of each set of shears is usually mounted on a driven shaft, the other shear members, as 2, being usually held in spring-pressed relation sidewise against members 1 and frictionally driven thereby.

Webs of paper are now being made in very wide widths and as a consequence the shaft which supports members 1 must be of relatively great length. I find that it is difficult to obtain dynamic balance of said shaft and that therefore such shaft has a "whipping" action, that is to say: it tends to flex and does not run true. The result is that the shear-cut members of the different sets at times become disengaged out of their overlapping relation and, when they attempt to return into engagement, one member will frequently ride on top of another instead of being in overlapping

relation. This will destroy the cutting edge of a member, as 2, and will also tend to cut the paper unevenly.

To overcome this difficulty I provide a sectionalized shaft for member 1 and provide a coupling means between the shaft sections that will allow a certain amount of misalignment of said sections without permitting the members of the set of shears to move out of overlapped relation.

In accordance with this, 3^a and 3^b indicate two shaft sections arranged and sustained end to end. In the case shown in Fig. 1 such shaft sections, which constitute a set, are supported by end bearings 4 and a center bearing 5. These shaft sections are connected by flexible coupling means, as 6, which latter is preferably a coupling known commercially as "Kanti-lever" coupling, and disclosed in Patents Nos. 1,328,366, 1,455,425 and 1,574,466. Power may be applied to the shaft sections by means of a pulley 7, or otherwise, and coupling 6 serves to transmit the power from one shaft section to another without transferring the "whipping" tendency. In order to adapt the machine to cut web sections of different widths the shear cut members are adjustable in a manner well understood and center bearing 5 is slidably mounted on a bracket, as 8, the adjustment of bearing 5 being effected by means of handwheel 9, gears 10 and 11 and threaded stem 12. The shaft sections and coupling means can therefore be adjusted lengthwise in unison.

It will now be understood that the flexible coupling means transmits power from one shaft section to the other and while tending to oppose the "whipping" action of the shaft sections, nevertheless allows a certain amount of misalignment thereof without, however, permitting the other members of a set to become disengaged. In consequence of this the machine may be run at a very high speed and may be used in connection with very wide webs.

In Fig. 2 there are three shaft sections, 3^a, 3^b and 3^c, two flexible couplings 6 and 6^a and two center bearings 5 and 5^a.

In Fig. 3 there are two shaft sections 3^a and 3^b, two center bearings 5 and 5^a and one flexible coupling 6.

In Fig. 4 the arrangement is the same as in Fig. 1, but here center bearing 5 is not adjustable.

In certain types of machines of this char-

acter both members of the shear-cut slitters are mounted on driven shafts and the invention can likewise be applied to this type of machine. In the exemplification shown in 5 Figs. 7, 8 and 9 there are two sets of shaft sections, one 30^a, 30^b and the other 300^a and 300^b. As there shown the sections of the same set are connected by flexible coupling means 6 and a plurality of sets of shear cut 10 slitting members 1 and 2 are employed in overlapping relation. In this form of the invention the two sets of shaft sections may be intergeared as by means of gears 70 and 700, power being derived, as before, from a 15 pulley 7. One geared set of shaft sections may also be adjustable toward and away from the other and it will be noted that end and center bearings 4 and 5 are connected together by beam 15 and that bearings 4 are adjustable 20 in guides 16 by means of screws 17. Also center bearings 5 of both sets of shaft sections are adjustable lengthwise, one on beam 15 by means of bolts 16 and the other on rod 17 by means of bolt 18.

25 I claim:

1. The combination with slitting means consisting of a plurality of sets of overlapping shears, of a plurality of shaft sections arranged and sustained end to end to support one of the members of each set of shears,

and flexible coupling means between the shaft sections to admit of misalignment of said sections but not of disengagement of the members of the sets of shears from overlapping relation.

2. The combination with slitting means consisting of a plurality of sets of overlapping shears, of a plurality of shaft sections arranged and sustained end to end to support one of the members of each set of shears, flexible coupling means between the shaft sections to admit of misalignment of said sections but not of disengagement of the members of the sets of shears from overlapping relation, and means to adjust the shaft sections and 40 coupling means lengthwise in unison.

3. The combination with slitting means consisting of a plurality of sets of overlapping shears, of two sets of shaft sections, each set of sections arranged and sustained end 45 to end to support one of the members of each set of shears, and flexible coupling means between the shaft sections of each set to admit to misalignment of the sections of each set but not of disengagement of the members of 50 the sets of shears from overlapping relation.

Signed at the borough of Brooklyn, in the county of Kings, city and State of New York, this 14th day of Sept., 1927.

JAMES A. CAMERON.
